UNIT FOR ELECTROLYTIC DENTAL
DESENSITIZATION

Adriano Bertolini, Bissone (Ticino), Switzerland

Filed Sept. 20, 1966, Ser. No. 3,938

Term of patent 14 years

(Cl. D24—1)

FIG. 1.

FIG. 2.

FIG. 3.

FIG. 4.

FIG. 5.

FIG. 1 is a front elevation of a unit for electrolytic dental desensitization showing my new design;

FIG. 2 is a side elevation thereof; the opposite side is substantially the same in appearance to the side shown;

FIG. 3 is a rear elevation thereof;

FIG. 4 is a top plan view thereof; and

FIG. 5 is a bottom plan view thereof.

I claim:

The ornamental design for a unit for electrolytic dental desensitization, as shown and described.
